UNITED STATES PATENT OFFICE.

JOHN N. ROBERTS, OF INDIANAPOLIS, INDIANA.

DESK-CURTAIN.

SPECIFICATION forming part of Letters Patent No. 447,415, dated March 3, 1891.

Application filed October 28, 1889. Serial No. 328,444. (No model.)

To all whom it may concern:

Be it known that I, JOHN N. ROBERTS, of Indianapolis, county of Marion, and State of Indiana, have invented certain new and useful Improvements in Desk-Curtains; and I do hereby declare that the following is a full, clear, and exact description thereof, reference being had to the accompanying drawings, in which like letters refer to like parts.

10 My invention relates to improvements in the construction of what are known as "flexible desk-curtains," and will be understood from the following description.

In the drawings, Figure 1 is a front view of my device, partly broken away, showing the arrangement of the links. Fig. 2 is a section on the line $x x$, Fig. 1. Fig. 3 is a side view of one of the links folded up, the dotted lines indicating the position of the link when partly open for passing the head on one end through the slot of the next link with which it is intended to be coupled.

15 In detail the desk-curtain is composed of slats s , jointed one upon another, as shown in Fig. 2.

b is the base, having staples st fastened in its upper edge.

20 h are metallic links formed of a single strip of metal with slots sl in each end, an offset made on one end, at least, below the slot, so that such end will pass through the slot of the next link. Of course this offset may be made on both ends, making the two ends of the link alike in this respect, but the offset is necessary at least at one end, or the links cannot be coupled as herein proposed. When coupled to form a chain, each link is reversed with reference to the direction of its head as compared with the one above and below it. 25 This is necessary in order to secure the hinging in a substantially straight line through the series of slats that compose the desk-curtain.

30 The manner of connecting the device together is as follows: The link is opened and passed through a staple st , driven into the base b . The ends are folded together and passed through the slat, so that the upper end of the double link will slightly project above the rounded edge of the slat so far as to allow the insertion of the end of the next link through the slots of the one in the slat. The

next link is now opened and the end with an offset below passed through the slots of the link below, turned about, and then folded up together in the manner shown in Fig. 3, and passed through the slat, care being taken in each instance in putting them together to reverse the respective ends of the adjacent links in the manner shown in Fig. 1. This operation is continued until a sufficient number of slats have been connected to form a curtain, and then the end of the last projecting link may be either left slightly protruded, or bent over upon the slat by a tap of the hammer. The link being made of thin annealed metal will allow this to be done without injury.

35 The construction herein shown dispenses entirely with the use of nails or screws, so that the contraction or expansion of the wood, which is quite common in curtains of this kind, owing to varying temperature and humidity of the atmosphere, can readily take place, as the slat can move readily on the links, the slits being made so as to allow this, and there will be no fixed point where such expansion and contraction will injuriously affect the wood, because it is nowhere directly connected to the link.

40 I am aware that desk-curtains have been connected together by strips or sheets of metal passing through slits formed in the slats, but these have been fastened to each slat by screws or nails, which furnish a point where there will be a strain brought upon the wood by the expansion and contraction before mentioned, and the slats cannot adjust themselves readily to each other, owing to such peculiar style of fastening.

45 What I claim as my invention, and desire to secure by Letters Patent, is the following:

1. The hinging-links h , having slots sl in each end, one end having an offset below the slot for permitting its passage through the slots of the next link, substantially as shown and described.

2. A chain for desk-curtains composed of a series of flat links h , having slots sl , connected together, the slotted heads of each alternate link reversed with respect to the head of the one above and below it, substantially as shown and described.

3. A desk-curtain wherein the slats are con-

nected by a chain composed of links h , formed of strips of metal having slots sl , such links having an offset below the slot to admit its passage through the slots of the next link, all 5 combined substantially as described.

4. A desk-curtain comprising a series of slats hinged together by links passing through slits in such slats, the links having slots sl in each end, and one end having an offset below its slot for permitting its passage through 10 the slots of the next link, all combined substantially as shown and described.

5. A desk-curtain composed of slats strung upon links hinged the one to the other, forming a continuous chain, the link passing entirely through the slat and provided with slots 15 at right angles to its length to receive the

end of the next link, substantially as shown and described.

6. A desk-curtain comprising a series of 20 slats connected by links of thin sheet metal, slots formed in the ends of the links at right angles to the length thereof, the shank narrowed at one end below the slot to admit its passage through the slots of the next link, 25 such chain flexible only in the line of its length, substantially as shown and described.

In witness whereof I have hereunto set my hand this 26th day of October, 1889.

JOHN N. ROBERTS.
